WO 2015126447 A1 8/2015

Primary Examiner — Marissa J Cash

(74) Attorney, Agent, or Firm — Avyno Law P.C.

(57)

CLAIM

I claim the ornamental design for a drone, as shown and described.

DESCRIPTION

FIG. 1 is a top perspective view of a drone.

FIG. 2 is a top view of the drone of FIG. 1.

FIG. 3 is a bottom view of the drone of FIG. 1.

FIG. 4 is a side view of the right side of the drone of FIG. 1.

FIG. 5 is a side view of the left side of the drone of FIG. 1.

FIG. 6 is a front view of the drone of FIG. 1; and,

FIG. 7 is a rear view of the drone of FIG. 1.

In the drawings, the broken lines depict portions of the drone that form no part of the claimed design.

1 Claim, 5 Drawing Sheets# US D862,285 S
